PRESSURIZED DISPENSING CONTAINER

Gilbert S. Jordan and Paul H. Mohr, Chappaqua, N.Y.,
assignors to Union Carbide Corporation, New York,
N.Y., a corporation of New York

Filed Oct. 15, 1968, Ser. No. 13,997

Term of patent 14 years

Int. Cl. D9—01

U.S. Cl. D9—9

FIGURE 1 is a perspective view of a pressurized dispensing container embodying our new design;

FIGURE 2 is a front elevational view;

FIGURE 3 is a top plan view; and

FIGURE 4 is a bottom plan view thereof.

The characteristic features of our design reside in the upper portions comprising the actuator assembly.

We claim:

The ornamental design for a pressurized dispensing container, as shown and described.
